To all whom it may concern:

Be it known that I, JAMES LYALL, of the city and State of New York, have invented a Design for Carpets, of which the following is 5 a specification.

This design is for a carpet, and relates to the appearance of the same.

The design is represented in the accompanying photograph.

10 The stripes *aa* are quite narrow, and run longitudinally of the fabric. Between these stripes there are the checks *HK*. The checks *H* alternate with the checks *K* both longitudinally and transversely of the fabric. The 15 checks *K* have a mottled appearance and zig-

zag diagonal lines, as shown. The checks *H* have diagonally-corrugated lines, as shown.

I claim—
